UNITED STATES PATENT OFFICE

166,910

RECLINING CHAIR FRAME

Aaron S. Goldberg, Philadelphia, Pa., assignor to
Bunting Glider Company, Philadelphia, Pa., a
corporation of Pennsylvania

Application March 28, 1952, Serial No. 19,093

Term of patent 14 years

(Cl. D15—11)

To all whom it may concern:

Be it known that I, Aaron S. Goldberg, a citizen of the United States, and a resident of Philadelphia, county of Philadelphia, State of Pennsylvania, have invented a new, original, and ornamental Design for a Reclining Chair Frame, of which the following is a specification, reference being had to the accompanying drawings, forming a part thereof, wherein:

Figure 1 is a perspective view of a reclining chair frame showing my new design;

Figure 2 is a side elevational view thereof; and
Figure 3 is a front elevational view thereof.

I claim:

The ornamental design for a reclining chair frame, substantially as shown.

AARON S. GOLDBERG.
